EVERETT L. THOMPSON, OF DOVER, NEW JERSEY, ASSIGNOR TO SYPHO-CHEMICAL SPRINKLER CORPORATION, OF CROTON-ON-HUDSON, NEW YORK, A CORPORATION OF NEW YORK.

AUTOMATIC FIRE-EXTINGUISHING APPARATUS.

1,245,134.

Specification of Letters Patent. Patented Oct. 30, 1917.

Application filed January 24, 1914. Serial No. 814,032.

To all whom it may concern:

Be it known that I, EVERETT L. THOMPSON, a citizen of the United States, and resident of Dover, Morris county, New Jersey, have made a certain new and useful Invention Relating to Automatic Fire-Extinguishing Apparatus, of which the following is a specification, taken in connection with the accompanying drawing, which forms part of the same.

This invention relates especially to automatic fire extinguishing apparatus in which the distributing system may comprise automatic sprinkler heads, hose connections or other distributing devices and is preferably provided with a priming or actuating tank which together with the distributing system itself may normally contain water or other non-freezing extinguishing liquid for low temperature work. Under emergency conditions when the liquid is withdrawn from the distributing system and connected actuating tank a suitable pressure change is caused in the actuating tank and adjacent parts of the system which may operate any desired emergency device, such as any chemical or other supplemental fluid supply device to supply additional extinguishing fluid to the distributing system.

The accompanying drawing shows in a somewhat diagrammatic way illustrative embodiments of this invention in elevation, parts being shown in section.

The distributing system may be of any desired type and may as indicated comprise one or more risers 1 to which may be connected various distributing pipes, such as 2 on which automatic sprinkler heads or devices 3 may be arranged at suitable intervals and the system may also comprise other distributing devices, such as hose distributing devices or connections 5 to which hose lines may be connected and operated when the valve 4 is opened. A suitable actuating or priming supply tank may be connected to any suitable part of the distributing system, when a wet pipe type of distributing system is used, so as to normally maintain the desired amount of extinguishing fluid therein. The actuating tank being preferably in any case large enough to supply the liquid required to compensate for any slight accidental leakage from the system, and also in many cases being of sufficient capac-

ity to furnish an initial supply of extinguishing liquid when the system first gets into action in the event of fire, for which purpose it is sometimes desirable to have this supply tank initially under considerable air pressure where a more forcible initial discharge of the extinguishing liquid is desired. The desired head may, however, be secured by gravity when the actuating or priming supply tank, such as 6, is carried up sufficiently beyond the distributing devices and connected, for instance, to the riser 1 of the distributing system, and in such an arrangement as is diagrammatically illustrated in the drawing it is desirable to provide in connection with the top of the tank or adjacent parts of the distributing system a suitable reduced equalizing device normally having a pin-hole or reduced equalizing venting passage for the slow escape or ingress of air caused by the expansion due to ordinary temperature changes. The equalizing valve 9 is shown for this purpose and is preferably of needle valve construction so as to allow the ready venting of air through the vent pipe 8 when filling the actuating tank and other parts of the distributing system in the first place with the water or other aqueous extinguishing liquid, 7, such as a suitable solution of soluble and substantially inert salts to reduce the freezing point of the liquid for low temperature service. This vent valve may of course be subsequently nearly closed to give the normal reduced vent passage desired.

Under emergency conditions when one or two of the automatic sprinkler heads open or when the other distributing devices are brought into play, the extinguishing liquid in the system is instantly available for putting out the fire and the discharge of this liquid involves the withdrawal of liquid from the substantially closed actuating tank so as to cause a decided pressure change therein and in the adjacent parts of the distributing system. Any suitable emergency devices may be used in connection with this actuating tank or connected parts for supplying additional extinguishing liquid to the system or for alarm purposes or both and the automatically operated emergency devices may be located at any convenient point and be connected with the actuating tank or connected parts in which the pressure

change takes place in any suitable way, as for instance by the suitable actuating connection or pipe 10 which may be normally filled with liquid and connected to the actuating tank 6 or the adjacent part of the distributing system, as is indicated, and also connected with the emergency or control device 12. This emergency device may comprise a control chamber which may if desired be normally filled with liquid and have a control diaphragm such as 13 of metal or other suitable material connected to the control stem 36 which may have thereon the flange 34 with which if desired a suitable spiral spring, such as 35 may coöperate to normally raise the stem and diaphragm when the parts are in the vertical position indicated in which they may be supported as by the bracket 14. Under normal conditions of the system the fluid in the control chamber is under considerable static or other pressure so as to exert considerable pressure on the control diaphragm. Under emergency conditions, however, the flow of extinguishing liquid from the distributing devices causes a pressure change in the actuating tank or connected parts and the actuating connection with these parts communicates this pressure change to the control device where the control diaphragm is thus caused to move because of its resiliency or the spring action or both, so as to operate the stem and any other suitable emergency devices desired. For instance a suitable alarm device may be readily actuated in this way as through suitable electric contacts, such as the movable or pivoted contact 32 actuated by movement of the stem so as to be swung into engagement with the stationary insulated contact 33 and thus close a circuit through the alarm device or bell 30 and battery 31 under emergency conditions. If desired also any similarly connected or actuated electrically operated emergency device may be used to supply supplemental extinguisher fluid to the distributing system and such an arrangement is somewhat diagrammatically shown in the drawing as comprising a supplemental supply pipe 22 which may be connected with the distributing system through the check valve 23, preferably having slight differential action so as to normally remain closed, but arranged so as to readily open and allow water from the city connection or other water supply pipe 24 to enter the distributing system when the valve or other connected emergency supply device 25 is actuated. This valve or device may be electrically actuated as by any suitable mechanism 26 released or operated by the magnets or solenoids 27 which may be in the circuit 28—29 in which any suitable battery 31 and the electric contacts 32, 33 are included.

65 Any supplemental fluid supply for the

distributing system, such as any pressure actuated supplemental fluid supply may be used to supply additional extinguishing fluid under emergency conditions and such an arrangement may be used in addition to or instead of the supplemental fluid supply above referred to. Such a chemical pressure actuated arrangement is shown in the drawing as comprising a chemical supply tank 38 which may be connected with the distributing system in any suitable way, this connection being preferably of an automatic venting character so as to prevent or minimize mixture of the liquid in the distributing system and the liquid used in the chemical supply tank. The connection 18, which may be used with advantage in my chemical or other pressure operated supply tank with the coöperating distributing system of the wet pipe or dry pipe type, may comprise a suitable cut-off or check valve such as 15 between the distributing system and the chemical supply tank and may preferably also comprise an automatic venting drain device such as 19 between the valve and tank. As shown in the drawing this venting device may comprise the venting float valve 17 coöperating with a suitable pin-hole or small sized venting or discharge opening which is normally open to allow the escape of air or other material while under emergency conditions when fluid fills this connection and drain device the float 18 connected to this valve rises and holds this float valve tightly closed against its seat. The connection may have the depending portion 20 extending within the chemical supply tank so that its receiving end 39 is adjacent the bottom of the tank where it may if desired be provided with a suitable strainer of wire gauze or the like. If desired also an air escape or venting aperture or connection with the upper part of the supply tank which is normally filled with air may lead to this connection 20 at any point between the tank and check valve. An air escape or venting aperture 21 may be formed in the connection inside the tank preferably adjacent the top of the air space therein so as to allow for the escape through this pin-hole aperture of any air or gases from time to time while not interfering with the emergency operation of the device. This chemical supply tank may contain the desired amount of any suitable carbonate solution 40 and a corresponding quantity of sulfuric or other suitable acid may be arranged within an acid container such as the tipping acid container 37 which may have a loosely fitting cover 41 and be normally retained in the inactive position indicated by the control stem 36. When, however, under emergency conditions this control stem is moved by the emergency or control device it is withdrawn from contact with 130

the acid container which is thus released and allowed to overturn so that the acid can mix in the desired way with the carbonate liquid. This effects the well known chemical reaction 5 forthwith and generates high pressure within this tank so as to force the extinguishing liquid through the connection into the distributing system to be discharged from the operating distributing devices and supplement 10 the extinguishing action of any other fluid that may have been originally contained in the distributing system.

This invention has been described in connection with a number of illustrative embodiments, forms, elements, materials, parts 15 and arrangements, to the details of which disclosure the invention is not of course to be limited, since what is claimed as new and what is desired to be secured by Letters

20 Patent is set forth in the appended claims.

I claim—

1. In automatic sprinkler apparatus, a distributing system normally charged with non-freezing extinguishing liquid and comprising 25 automatic sprinkler heads and hose distributing devices, an actuating supply tank containing said extinguishing liquid and connected to the upper part of said distributing system, a reduced area equalizing 30 device connected to the upper part of said actuating tank to permit a pressure change to take place in said actuating tank and adjacent parts on the emergency operation of the system, an emergency device comprising 35 a control chamber and a coöperating movable control diaphragm member, an actuating connection between said emergency device and said distributing system adjacent said actuating tank to normally put said 40 control member under pressure, a supplemental fluid supply for said distributing system comprising a chemical supply tank, a tipping acid container coöperating with said chemical supply tank and a control 45 stem operatively connected to said control diaphragm member and normally in the path of said acid container to effect the operation of said chemical supply tank when said emergency device receives its emergency 50 actuation.

2. In actuating sprinkler apparatus, a distributing system normally charged with extinguishing liquid and comprising automatic distributing devices, an actuating supply tank containing said extinguishing liquid and connected to the upper part of said distributing system, a reduced area equalizing device connected to the upper part of said actuating tank to permit a pressure change to take place in said actuating tank and adjacent parts on the emergency operation of the system, an emergency device comprising a movable control diaphragm member, an actuating connection between 55 said emergency device and said distributing 60 system.

system adjacent said actuating tank to normally put said control member under pressure, a supplemental fluid supply for said distributing system comprising a chemical supply tank, an acid container coöperating 70 with said chemical supply tank and a control stem operatively connected to said control diaphragm member to effect the operation of said chemical supply tank when said emergency device receives its emergency 75 actuation.

3. In automatic sprinkler apparatus, a distributing system normally charged with extinguishing liquid and comprising distributing devices, an actuating supply tank 30 containing said extinguishing liquid and connected to the upper part of said distributing system, a reduced area equalizing device connected to the upper part of said actuating tank to permit a pressure change 35 to take place in said actuating tank and adjacent parts on the emergency operation of the system, an emergency device comprising a movable control member, an actuating connection between said emergency device and 40 said distributing system to normally put said control member under pressure, a supplemental fluid supply for said distributing system comprising a chemical supply tank, an acid container coöperating 45 with said chemical supply tank and operatively connected to said control member to effect the operation of said chemical supply tank when said emergency device receives its emergency 50 actuation. 100

4. In automatic sprinkler apparatus, a distributing system normally charged with extinguishing liquid and comprising distributing devices, an actuating supply tank containing said extinguishing liquid and connected to the upper part of said distributing system, a reduced area equalizing device connected to the upper part of said actuating tank to permit a pressure change to take place in said actuating tank and adjacent parts on the emergency operation of the system, an emergency device comprising a movable control member, an actuating connection between said emergency device and 105 said distributing system to normally put 110 said control member under pressure, a supplemental fluid supply for said distributing system and operatively connected to said control member to effect the operation of said supplemental fluid supply when said 115 emergency device receives its emergency actuation.

5. In actuating sprinkler apparatus, a distributing system normally charged with extinguishing liquid and comprising automatic distributing devices, an actuating supply tank containing said extinguishing liquid and connected to the upper part of said distributing system, a reduced area equalizing device connected to the upper 120 part of said actuating tank to permit a pressure change to take place in said actuating tank and adjacent parts on the emergency operation of the system, an emergency device comprising a movable control diaphragm member, an actuating connection between 125 said emergency device and said distributing 130 system.

part of said actuating tank to permit a pressure change to take place in said actuating tank and adjacent parts on the emergency operation of the system, an emergency device comprising a movable control diaphragm member, an actuating connection between said emergency device and said distributing system adjacent said actuating tank, a supplemental fluid supply for said distributing system comprising a chemical supply tank, an acid container coöperating with said chemical supply tank and a control stem operatively connected to said control diaphragm member to effect the operation of said chemical supply tank when said emergency device receives its emergency actuation.

6. In automatic sprinkler apparatus, a distributing system normally charged with extinguishing liquid and comprising distributing devices, an actuating supply tank containing said extinguishing liquid and connected to the upper part of said distributing system, a reduced area equalizing device connected to the upper part of said actuating tank to permit a pressure change to take place in said actuating tank and adjacent parts on the emergency operation of the system, an emergency device comprising a movable control member, an actuating connection between said emergency device and said distributing system, a supplemental fluid supply for said distributing system comprising a chemical supply tank, an acid container coöperating with said chemical supply tank and operatively connected to said control member to effect the operation of said chemical supply tank when said emergency device receives its emergency actuation.

7. In automatic sprinkler apparatus, a distributing system normally charged with extinguishing liquid and comprising distributing devices, an actuating supply tank containing said extinguishing liquid and connected to the upper part of said distributing system, a reduced area equalizing device connected to the upper part of said actuating tank to permit a pressure change to take place in said actuating tank and adjacent parts on the emergency operation of the system, an emergency device comprising a movable control member, an actuating connection between said emergency device and said distributing system, a supplemental fluid supply for said distributing system and operatively connected to said control member to effect the operation of said supplemental fluid supply when said emergency device receives its emergency actuation.

8. In automatic fire extinguishing apparatus, a distributing system normally charged with extinguishing liquid and comprising automatic sprinkler heads and hose distributing devices and an actuating supply

tank containing extinguishing liquid connected to the upper part of said distributing system, and having its upper part substantially closed under emergency conditions to cause a suction pressure change in said actuating tank and adjacent parts on the emergency operation of the system, an emergency device, an alarm device operatively connected with said emergency device, an actuating fluid connection between said emergency device and said distributing system adjacent said actuating tank to normally transmit fluid pressure thereto, a supplemental fluid supply for said distributing system comprising a chemical supply tank, an automatically closing venting connection between said chemical supply tank and said system, an acid container coöperating with said chemical supply tank to effect the operation of said supplemental fluid supply when said emergency device receives its emergency actuation.

9. In automatic fire extinguishing apparatus, a distributing system normally charged with extinguishing liquid and comprising distributing devices and an actuating supply tank containing extinguishing liquid connected to the upper part of said distributing system, and having its upper part substantially closed under emergency conditions to cause a suction pressure change in said actuating tank and adjacent parts on the emergency operation of the system, an emergency device, an actuating fluid connection between said emergency device and said distributing system adjacent said actuating tank to normally transmit fluid pressure thereto, a supplemental fluid supply for said distributing system comprising a chemical supply tank and an acid container coöperating with said chemical supply tank to effect the operation of said supplemental fluid supply when said emergency device receives its emergency actuation.

10. In automatic fire extinguishing apparatus, a distributing system normally charged with extinguishing liquid and comprising distributing devices and an actuating supply tank containing extinguishing liquid connected to the upper part of said distributing system, and having its upper part substantially closed under emergency conditions to cause a pressure change in said actuating tank and adjacent parts on the emergency operation of the system, an emergency device, an actuating connection between said emergency device and said distributing system adjacent said actuating tank, a supplemental fluid supply for said distributing system connected to said emergency device to be operated when said emergency device receives its emergency actuation.

11. In automatic sprinkler apparatus, a distributing system normally charged with

extinguishing liquid and comprising distributing devices, an emergency device comprising a movable control member, an actuating connection between said emergency device and said distributing system to normally put said control member under liquid pressure and to transmit thereto a pressure change on the emergency operation of the system, a supplemental fluid supply for said

distributing system and a control means 10 connected to said control member to allow the operation of said supplemental fluid supply when said emergency device receives its emergency actuation.
